BENJAMIN B. DUDLEY, OF VISALIA, CALIFORNIA.

FOLDING CAMP TABLE.

1,417,891.

Specification of Letters Patent. Patented May 30, 1922.

Application filed June 27, 1921. Serial No. 480,832.

To all whom it may concern:

Be it known that I, BENJAMIN B. DUDLEY, a citizen of the United States, and resident of Visalia, county of Tulare, and State of California, have invented a new and useful 5 Folding Camp Table, of which the following is a specification.

The present invention relates to a folding camp table and has for its primary object 10 to provide a table of this character which may be folded and conveniently carried upon the running board of an automobile.

One of the salient features of the invention resides in the construction, which will 15 enable the table when folded to act in the capacity of a carrying compartment for various camping accessories, even food stuffs, cooking equipment, and the like, and in this connection the peculiar arrangement and co- 20 operative relationship of the parts of the table are such as to make it possible to associate the table, when folded, with at least two chairs or stools, which are made to receive the ends of the table for confining the 25 same on the running board of the automobile.

The invention possesses further features which will appear as the description now proceeds with reference to the preferred embodiment of the invention shown in the accompanying drawing, and in which Figure 30 1 is a view in side elevation of the running board of an automobile showing the table as folded and carried thereby; Figure 2 is a perspective view of the table set up and 35 showing one of the stools; Figure 3 is a plan view of the underside of the table showing the legs thereof folded; Figure 4 is an enlarged detail view of one of the clips of the stool which is used to mount the 40 stool in fixed relation to the running board of an automobile; Figure 5 is an enlarged detail view of the same clip shown in Figure 4 looking at a different side of the same; Figure 6 is a detail view of one of the leg 45 braces; Figure 7 is an end view of one of the leg braces showing the V-shaped notch which is provided in one end of each of the braces; and Figure 8 is a detail view of the horizontal brace rod for the legs.

50 Referring now to the drawings in detail, and as best shown in Figure 1, the table, when folded, is adapted to occupy a position on the running board (A) of an automobile body (B). The table, as above 55 stated, is of the folding type so that the same may occupy a relatively small space

when not in use and yet capable of being assembled in the most convenient manner to provide a rigid structure having a top surface capable of providing a relatively 60 large area so that a number of people may sit around the same. In realizing these advantages it is suggested to construct the table, as will best be seen in Figures 2 and 65 3, of a plurality of relatively long board sections (1), (2) and (3), the length of which preferably corresponding to the length of the running board of the automobile. The sections are arranged side by side and hinged together by two sets of end hinges (4) and a 70 set of intermediate hinges (5). These hinges will permit the board sections (1) and (3) to be folded in vertical parallel relation one to the other, and at right angles to the intermediate section (2) to provide a relatively 75 long box like compartment, with the sections (1) and (3) acting as the sides of the box and the section (2) acting as a bottom for the box.

To carry the table when folded upon the 80 running board (A) of the automobile and at the same time conveniently close the ends of the box like compartment when the table is folded, it is suggested to take advantage of a pair of stools (6) each of which having 85 the customary legs (7) braced as at (8), and having a seat (9). In positioning the stools to co-operate with the table when folded to act as an end closure for the box like compartment above mentioned, each 90 stool is laid on its side, the legs (7) thereof straddling the ends of the table at a line parallel to the upturned board sections (1) and (3) as best shown in Figure 1. In this way the legs (7) hold the board sections (1) and (3) in upturned position with the sets of hinges (4) and (5) preventing 95 collapsing of the same toward each other, and with the seat (9) closing the end of the compartment thus provided.

100 Each stool is provided with an angle clip (10) riveted, screwed, or otherwise fixed to one of the leg braces of the stool, as at (11), having an inwardly presented end terminating in an L-shaped extremity (12) providing an abutment for the bolt (13) of the thumb screw (14) which is threaded in an opening in the clip. The angularity of the clip is such that when the stools are laid on their side on the running board the clip 105 will be presented under the running board with the thumb screws (14) in vertical posi-

tion, so that by screwing up on the same they will clamp the stools to the running board, as best shown in Figure 1. As will be seen, this will rigidly mount the table to 5 the running board and confine the same thereon with the absence of any longitudinal movement or transverse movement relative to the running board.

In assembling the table for eating or 10 other purposes when the occasion arises, the thumb screws (14) of the stools will be loosened to enable the stools to be slid away from the ends of the table, which will release the same so that it may be lifted from 15 the running board, whereupon it may be laid bottom side up on the ground with the board sections (1) and (3) laid down on the same plane as the intermediate board section (2), thus making the table top.

20 Carried on the underside of the intermediate board section (2) and folded flat there-against when inactive are the legs for the table, which preferably comprise two sets of folding leg members, each set comprising a pair of legs (15) and a pair of brace members (16) pivoted as at (17) to the leg members, and pivoted as at (18) to the intermediate board section. In setting up the legs, the leg members (15) of each 25 set are first raised vertically, then the brace members (16) of each set are swung in the same direction about their pivots (18) until they are presented transversely of the board sections (1), (2) and (3) in parallel relation one to the other, and with their pivoted 30 ends over-lapping. The leg members (15) are then crossed by folding them inwardly, which will present them as shown in Figure 2. Each of the leg members (15) in both 35 sets are constructed with openings (19) so that when the leg members are folded inwardly and crossed, the openings (19) in each set will register with each other so that the rod (20) may be passed through 40 the openings in both sets, and by threading a wing nut (21) to the ends of the rod, the legs may be pulled toward each other so that the diagonal braces (22), which are crossed between the two sets of legs, may be 45 held in place and in this way provide a rigid structure for the legs. Each of the brace members (22) are provided with V-shaped notches (23) in one of their ends which is adapted to straddle the rod (20) 50 as shown in Figure 2. The opposite ends of the brace members are beveled, as at (24), to abut against the over-lapping pivoted ends of the brace members (16). The 55 revolved position of the brace members (16) and the leg members (15) are shown in dotted lines in Figures 2 and 3. These dotted lines also show the relative position of the diagonal braces (22), and it will be 60 clear from these two figures how the beveled ends (24) of the braces (22) bear against

the over-lapped ends of the brace members (16) when the wing nuts (21) of the rod (20) are tightened up to prevent any attempt of the legs to collapse.

The stools may be used for seating arrangement around the table, as shown in 70 Figure 2.

While the box like structure made by folding the table on the running board has no 75 top, it may be used with one if desired, or a canvas or the like cover may be used in its stead.

The folded positions of the leg members (15) and the brace members (16) are best 80 shown in Figure 3, where it will be noticed the relative positions of the same are so arranged as to enable them to be nested to occupy a small transverse space without over-lapping or otherwise interfering with the board sections (1) and (3), leaving them 85 free to be turned up in making the box like structure referred to.

It is of course to be understood that the 90 braces (22) together with the rod (20) are carried loose in the box like structure when the table is folded on the running board, and, as previously stated, any other equipment may be carried in this compartment if desired.

I claim:

1. In a folding table and in combination with a pair of non-collapsible stools, a plurality of board sections hinged together with the two side sections adapted to fold lengthwise of the intermediate section to provide 100 an open ended box like structure, said non-collapsible stools adapted to be layed on their side and fixed to the running board of an automobile with the legs of the stools presented toward each other and adapted to 105 receive the table when folded and with the seats of the stools providing end closures for the box like structure, said intermediate board section having mounted on its underside two sets of legs adapted to be collapsed 110 and nested upon the surface of the intermediate board section when the table is folded, but capable of overlying both of the side board sections when the table is set up, whereby the legs and their mountings may 115 maintain all of the board sections in substantially the same plane to provide a table surface with the legs supporting the same.

2. In a folding table and in combination with a pair of non-collapsible stools, a plurality of board sections hinged together with the two side sections adapted to fold lengthwise of the intermediate section to provide 120 an open ended box like structure, said non-collapsible stools adapted to be layed on their side and fixed to the running board of an automobile with the legs of the stools presented toward each other and adapted to receive the table when folded and with the 125 seats of the stools providing end closures 130

- for the box like structure, said intermediate board section having mounted on its underside two sets of legs adapted to be collapsed and nested upon the surface of the intermediate board section when the table is folded, but capable of overlying both of the side board sections when the table is set up, whereby the legs and their mountings may maintain all of the board sections in substantially the same plane to provide a table surface with the legs supporting the same,

and braces for said legs adapted to maintain the mountings for the legs across all of the board sections and a longitudinal tie rod for holding the braces in place.

3. The combination as set forth in claim 1 and in which each of the stools include angle clips made to engage the running board of an automobile and clamp the stools thereto.

BENJAMIN B. DUDLEY.
